BANDAGE

Abraham Steinert, Berlin, Germany, assignor to
the firm P. Beiersdorf & Co., Inc., New York,
N. Y.

Application July 23, 1932, Serial No. 624,253,
and in Germany August 7, 1931

1 Claim. (Cl. 128—268)

This invention relates to a preferably elastic bandage coated with adhesive as used for winding on parts of the body, for example, for winding on the lower limb or the knee.

5 There are already known bandages in which the adhesive is applied over the entire breadth of the bandage, in certain cases leaving uncoated narrow marginal strips. In the use of such bandages frequently there is occasioned irritation of the skin of very sensitive persons. This irritation may give rise to inflammation, eczema or the like due to the fact that no air can enter 10 between the bandage and the skin or rather between the adhesive layer and the skin. Further, the removal of such a bandage from the bandaged part of the body is disagreeable and sometimes painful. The same drawbacks are experienced 15 with bandages which are not provided with adhesive over their entire breadth but which present longitudinal coated strips separated by uncoated strips.

The present invention obviates the aforesaid drawbacks by reason that the adhesive is applied over only about one half of the breadth of the 20 bandage—from the edge of the bandage to the centre line—while the other half of the bandage is uncoated. It is thus rendered possible so to wind the bandage that, as usual, successive plies overlap, but in contrast with previous forms the 25 adhesive does not come in contact with the skin save for the first coil of the winding.

In a preferred embodiment the initial end portion of the bandage, for example, a part of about 30 the length of about one coil, may be entirely uncoated so that also at the initial end there is no contact between the skin and the adhesive strip.

If so desired, at the terminal end portion of the bandage adhesive may be applied over the entire breadth of the bandage so as to facilitate the fixing of the terminal end.

Also the coating may be applied stripwise—in at least two strips—in such wise that the coated strips are separated from one another by an uncoated longitudinal strip.

45 Several embodiments according to the invention are illustrated by way of example in the accompanying drawing in which Fig. 1 shows a bandage in which the initial end is uncoiled. Fig. 2 is a similar view showing a modified form. Fig. 3 is a similar view showing another modification. Fig. 4 shows the use of the bandage at the commencement of the winding operation. Fig. 5 shows the terminal end of the bandage at about the completion of the winding operation.

55 The bandage *a* shown in Fig. 1 is coated for its entire length with a longitudinal strip *b* of adhesive, the breadth *c* of which strip constitutes about one half of the total breadth of the bandage.

60 The bandage *a'* shown in Fig. 2 is also coated

with a strip *b'* of adhesive of about one half the breadth of the bandage. In this modification the initial end *d* of the bandage is entirely uncoated with adhesive.

In the bandage *a* shown in Fig. 3 the adhesive is distributed over two narrower strips *b*², *b*³. These two strips are separated from one another by a narrow uncoated strip *b*⁴. The collective breadth *b*⁵ of the strips *b*², *b*³, *b*⁴ amount to about one half of the total breadth of the bandage.

In applying the bandage to a part of the body, for example, the leg, the adhesive strip is so located that in the winding in which the successive coils overlap the coated strip contacts only with the bandage ply beneath the same but not with the skin of the body. This will be clear for example from Fig. 5 which shows the bandage *a* practically completely wound on 80 the leg *e*. The overlapping portions of the bandage are of about half of the breadth of the entire bandage, that is of the breadth of the coated strip. The skin of the leg over which the bandage is wound is therefore not 85 in contact with the adhesive or is in contact only with the adhesive coating of the first coil, so that the bandage can be readily removed from the body without causing pain to the patient. Also, there is no irritation such as is 90 liable to occur when applying an adhesive plaster to the skin of a sensitive person.

In Fig. 4 there is shown the use of the bandage according to Fig. 2. The initial end *d* of the bandage *a'* is wound about the portion of 95 the body in the manner usual with ordinary uncoated bandages. The adhesive *b'* therefore contacts only with an underlying layer of the bandage without making contact with the skin. In this way at the commencement of the winding of the first ply direct contact of the adhesive with the skin is avoided.

The terminal end of the bandage can be secured in any desired manner after the winding operation to the body of the patient; for 105 example, the terminal end can be secured by aid of a plaster. Also, as shown in Fig. 5, the terminal portion *f* of the bandage can be coated with adhesive over its entire breadth so that the bandage can be secured to the body 110 at the terminal end.

I claim:—

A bandage for use for winding on parts of the body, comprising an adhesive coated on said bandage, said adhesive coating about one half of the breadth of said bandage—from one marginal edge to the central line—, the other half of said bandage being uncoated.

ABRAHAM STEINERT.
